UNITED STATES PATENT OFFICE.

WILLIAM E. COLWELL, OF ZION, ILLINOIS.

BUBBLE BLOWER.

Application filed August 6, 1926, Serial No. 127,637. Renewed September 19, 1928.

This invention relates to certain novel improvements in bubble blowers, which I call a bubble shooter, and more particularly to an arrangement of parts that will permit the successive discharge of bubbles.

Among the salient objects of this invention is the production of an article of this character wherein provision is made for conveying the soap solution in a uniform stream over and around the outlet end portion of the blower pipe where a membrane may be formed by dipping the article in the soap solution to fill it. Then when a bubble is discharged by blowing through the bubble pipe a membrane is left on the wiping shelf or in the end of the blower pipe ready for the formation of another bubble and should it miss a membrane may be formed by wiping action of the finger tip over the wiping plate in the direction of the outlet end portion of the blower pipe.

A further object of the invention resides in the novel manner of associating a soap suds container with a blower pipe in position where the soap suds confined in the container finds exit contiguous the outlet end portion of the blower pipe in a position to be engaged by the finger tip, if necessary, for reasons hereinafter understood.

Other objects will appear hereinafter.

30 The invention consists in the combination and arrangement of parts to be hereinafter described and claimed.

The invention will be best understood by reference to the accompanying drawings illustrating the preferred form of my invention and in which:

Fig. 1 is a perspective view of the invention.

Fig. 2 is a longitudinal vertical sectional detail view of the same.

40 Fig. 3 is a sectional detail view taken substantially on line 3—3 of Fig. 2.

Fig. 4 is an elevational view of a wiping plate embodied in the invention.

To accomplish the various objects of the invention I provide a blower pipe 10 which is formed of such material as will not be injurious to the lips or mouth of the user. This blower pipe 10 defines an outlet end portion 11 tapered downwardly from the top side 12 of the blower pipe and outwardly toward the lower surface 12' of the blower pipe to define an inclined end surface 13. The outlet end portion 11 defines a bevelled edge portion 14 which extends around the discharge mouth 15 of the blower pipe 10.

Associated with the blower pipe 10 is a

neck 16 substantially U-shaped in form and defining a curved intermediate portion 17 adapted for snug engagement with the lower surface 12' of the outlet end 11 of the blower pipe 10. This neck 16 defines tabs 18 adapted to be connected, by soldering or welding or the like, to adjacent wall portions 19 of a container 20 including a cover 21 defining an air inlet opening 22. This container 20 defines a bottom wall 23 which is curved to conform to the curvature of the top surface 12 of the outlet end portion of the blower pipe 10 whereby the container 20 may be snugly seated upon the blower pipe 10 and be retained in such position through the medium of the neck 16. This container defines in its wall portion 24 spaced outlet openings 26 through which the soap suds, confined in the container, is adapted to find exit and flow downwardly over the bevelled edge 14 on top and opposite sides of the outlet end portion 11 onto a wiping plate 27 formed as a continuation of the neck 16. This wiping plate 27 has its outer end portion 28 curved downwardly to alleviate a sharp edge and aid in the speedy discharge of bubbles. From the end portion 28 the edge portions 29 of the wiping plate curve upwardly and terminate into corner portions 30 of the neck 16. These corner portions, which are disposed at the junction between the edge portions 29 and the neck 16, are flared outwardly from the bevelled edge 14 whereby to define together with the bevelled edge 14 channels 31 on opposite sides of the outlet end portion 11 and through which the soap suds is adapted to flow from the container onto the wiping plate 27.

To govern the flow of soap suds through the outlet openings 26 I confine in the container 20 an absorbent strip of material 32 whereby the soap suds in order to find exit through the outlet openings 26, will have to first pass through the strip 32 in its passage to the outlet openings 26. This arrangement provides a slow stream of soap suds over the bevelled edge 14 and down the channels 31.

To formulate a bubble the bubble blower, above described, is operated in the following manner:

The cover 21 is removed from covering position with respect to the container 20 to permit a quantity of soap suds to be confined in the container 20 after which the cover 21 is placed, if desired, in covering position with respect to the container 20. The soap suds will be absorbed by the strip 32 and after this

strip 32 has absorbed its full capacity of soap suds, the superfluous soap suds will find slow exit through the outlet openings 26 over the bevelled edge 14 through the channels 31 and 5 onto the wiping plate 27. After a certain amount of soap suds has been confined upon the wiping plate 27 if necessary the user may place the tip of his finger inwardly of the curved end portion 28 and draw his finger 10 tip toward the outlet end portion 11 in wiping action on the plate 27 whereby to wipe a certain amount of soap suds onto and over the mouth of the outlet end portion thereby defining a thin membrane over this mouth. 15 The blower pipe 10 is now placed with the end portion 10' in the mouth and by blowing through the pipe 10 a bubble will start to form at the outlet end portion 11. As this bubble grows in size its weight will have a tendency 20 to move the bubble downwardly. In this downward movement the bubble (not shown) may have its inner end portion over the opening 15 and up the container 20 and resting upon the wiping plate 27 and thereby be 25 steadied.

For exceptionally large bubbles it is advisable to reverse the blower pipe so as to dispose the container at the under side thereof whereby the wiping plate 27 will not interfere with the formation of the bubble, but will help to hold same in position. It is pointed out that the air inlet opening 22 is of such size as will not permit any great amount of soap suds to find exit therethrough and so 35 will aid in making the bubble when the blower pipe 10 is reversed in the position above mentioned.

While I have illustrated and described the preferred form of construction for carrying 40 my invention into effect, this is capable of variation and modification without departing from the spirit of the invention. I, therefore, do not wish to be limited to the precise details of construction set forth, but 45 desire to avail myself of such variations and modifications as come within the scope of the appended claims.

Having thus described my invention, what 50 I claim as new and desire to protect by Letters Patent is:

1. In a device of the character stated, a tubular stem, and a plate extending beyond the outlet end of the stem at the lower portion thereof, said plate having a neck embracing

the lower portion of the stem, the plate flaring 55 laterally at its juncture with the neck and the stem extending beyond the neck and defining with the flared portion of the plate channels extending about the lateral portions 60 of the outlet end of the stem.

2. In a device of the character stated, a tubular stem, a plate extending beyond the outlet end of the stem at the lower portion thereof, said plate having a neck embracing 65 laterally at its juncture with the neck and the stem extending beyond the neck and defining with the flared portion of the plate channels extending about the lateral portions of the outlet end of the stem, and a container fitting about the upper portion of the stem above said neck, said container being provided with outlet openings in its outer end and at opposite sides of the transverse center 70 thereof.

3. In a device of the character stated, a tubular stem, a plate extending beyond the outlet end of the stem at the lower portion thereof, said plate having a neck embracing 75 laterally at its juncture with the neck and the stem extending beyond the neck and defining with the flared portion of the plate channels extending about the lateral portions 80 of the outlet end of the stem, and a container fitting about the upper portion of the stem above said neck and secured to the neck, said container being provided with outlet 85 openings in its outer end and at opposite sides of the transverse center thereof.

4. In a device of the character stated, a tubular stem, a plate extending beyond the outlet end of the stem at the lower portion thereof, said plate having a neck embracing 90 laterally at its juncture with the neck and the stem extending beyond the neck and defining with the flared portion of the plate channels extending about the lateral portions of the outlet end of the stem, the neck having upwardly extending tabs, and a container 95 mounted on the upper portion of the stem above the neck and secured in position by said tabs, said container having openings through its outer end and at opposite sides 100 of the transverse center thereof.

In testimony whereof I affix my signature.
WILLIAM E. COLWELL.
